UNITED STATES PATENT OFFICE.

CHARLES E. STELLER, OF MILWAUKEE, WISCONSIN.

TRANSOM-LIFTER.

SPECIFICATION forming part of Letters Patent No. 358,579, dated March 1, 1887.

Application filed November 16, 1886. Serial No. 219,009. (No model.)

To all whom it may concern:

Be it known that I, CHARLES E. STELLER, of Milwaukee, in the county of Milwaukee and State of Wisconsin, have invented new and useful Improvements in Transom-Lifts; and I do hereby declare the following to be a full, clear, and exact description of said invention, reference being had to the accompanying drawings, and to the letters or figures 10 of reference marked thereon, which form a part of this specification.

Figure 1 represents a front view, and Fig. 2 a side view, of a transom-lift embodying my improvements; and Figs 3 and 4 are details.

Like parts are represented by the same reference letters throughout the several views.

A represents that part of the transom-frame with which the transom-lift is connected. B represents that part of the casing to which the 20 transom-lift is attached.

By my improvement the guide-bearing C is made flat instead of round, and the sliding bracket D is provided with an elongated aperture, a, for the reception of the guide-bearing C, to which it is nicely fitted. An aperture is formed at c' in the bracket D for the reception of the link E. The bracket D being thus held in its proper position by the flat guide-plate, I am enabled to use the peculiar connecting-link E (shown of cylindrical form and having loosely-fitting circular bends b and d) without liability of said bracket D turning or inclining, as said bracket is not in any way dependent on the link E to prevent it from 30 turning, while with a round or cylindrical guide-bearing, C, a closely-fitting joint between the link E and the sliding bracket D is necessary to retain said parts in their proper position.

To enable me to adjust the link E upon the transom-arm F nearer to or farther from the transom, as may be required to conform to moldings of various widths, I have provided said arm F with a series of retaining-notches, 45 g g, which are formed in the ridge or elevation h, whereby it is obvious that the upper end of the link E may be moved toward or from the end of said arm F and adjusted at any point in line with the lifting-rod G. In forming the 50 eye d the end of the rod of which it is formed is so bent as to leave a small space, a', between

the rod and the arm F for the reception of the ridge h. When inserting the arm F it is so turned as to bring the ridge h into the space a' when it is moved to the desired notch g. It is 55 then turned in the position shown and secured to the transom-frame, in which position the notches g engage upon the respective sides of the link and hold it in place.

The flat guide-bearing C is preferably secured to the casing upon two supporting blocks or washers, H H, by ordinary screws, I I. The plate C may, however, be elevated or supported upon shoulders or fastening-plates formed in one piece therewith and the separate blocks H H dispensed with.

The lower end of the lifting-rod G is supported in an open thimble or bracket, J, in which it has two bearings, b' b', formed in the respective sides of the bracket or thimble. 70 Midway between the two bearings b' b' is a hand-screw, K, which, as it is screwed inward, impinges against the lifting-rod G, whereby the lifting-rod G is fastened at the desired point of adjustment.

A twofold object is attained by the open bracket or thimble J not attained by a solid-rod support of the ordinary construction. First, by the form shown I am enabled to rivet or upset the inner end of the adjusting-screw K, 80 so that it cannot be accidentally withdrawn; and, second, the frictional contact of the lifting-rod G is increased by having two bearings instead of one, whereby the same is rigidly held at the required place of adjustment by 85 the hand-screw without the aid of notches or depressions.

It is obvious that when the screw K is turned down firmly against the lifting-rod G, midway between the two bearings b' b', the pressure of 90 the screw thus applied against said rod, at a point where there is no direct resistance, has a tendency to slightly bend said lifting-rod rearward between said bearings b' b', and the rod is consequently held much more firmly than it 95 would be possible to hold it in a solid bracket of the ordinary construction.

The several central or intermediate rod-supporting brackets, L, between the guide-bar C and the adjusting-screw K, are so formed that 100 they may be cast in shape to be attached without drilling holes for the screws. As the screw-

holes and the aperture for the lifting-rod are formed at right angles to each other, it becomes difficult to make such brackets in the ordinary form without drilling either the screw-holes 5 or the hole for the rod.

Notches $h' h'$ are cast in the upper and lower ends of the fastening-plate M for the reception of the screws, whereby I am enabled to cast such parts in shape to be used without any ma- 10 chine-work thereon.

I am aware of the state of the art as shown in Patent No. 148,538, and make no claim to the device therein shown; neither do I claim a two-armed bracket for supporting the lifting- 15 rod of a transom-lift, broadly, nor a set-screw upset upon its inner end, as they have previously been used in various ways.

What I claim as new, and desire to secure by Letters Patent, is—

20 1. In a transom-lift, the combination of the transom-arm F, having ridge or elevation h , provided with a series of link-retaining notches, $g g$, for the reception of the upper eye of the connecting-link E, and connecting-link E,

communicating between said arm and the lifting-rod, substantially as shown and described. 25

2. In a transom-lift, the transom-arm F, having a ridge or elevation, h , provided with a series of link-retaining notches, $g g$, with a connecting-link, a bracket, and an elevated 30 guide-bearing, substantially as and for the purpose set forth.

3. In a transom-lift, the device for locking the lifting-rod, consisting in the combination of the bracket J, having two rod-bearing ap- 35 ertures, $b' b'$, for the reception of the lifting-rod G, lifting-rod G, and hand-screw K, ar- ranged in a screw-threaded aperture at right angles to said lifting-rod and adapted to im- pinging on said lifting-rod midway between said 40 bearings $b' b'$, in the manner and for the purpose set forth.

In testimony whereof I affix my signature in presence of two witnesses.

CHARLES E. STELLER.
